UNITED STATES PATENT OFFICE

2,435,920

BALANCED GRANULAR MICROPHONE

Louis R. Burroughs, South Bend, Ind., assignor
to Electro-Voice Manufacturing Co., Inc., South
Bend, Ind., a corporation of Indiana

Application September 20, 1943, Serial No. 503,093

8 Claims. (Cl. 179—122)

1

This invention relates to improvements in microphones, and more particularly to microphones of the carbon button type.

Carbon button microphones are frequently subject to harmonic distortion. Thus the diaphragm of the microphone, by virtue of its relation to the carbon granules of the microphone at one face thereof, is subject to unequal and unbalanced pressures and to an unbalanced vibration-damping action. This unbalance prevents true response of the diaphragm to sounds impinging thereon, and distortion results. It is the primary object of this invention to reduce such distortion and obtain an improved response characteristic in a microphone of this type.

A further object is to provide a microphone with means for balancing the diaphragm thereof with respect to pressures and vibration-damping influences thereon.

A further object is to provide means for damping the vibrations of a microphone to limit said vibrations to those imparted thereto by impingement of sound thereagainst.

Other objects will be apparent from the description, drawing and appended claims.

Fig. 1 is an axially transverse sectional view of a microphone, taken on line 1—1 of Fig. 2.

Fig. 2 is a sectional view taken on line 2—2 of Fig. 1.

Referring to the drawing, which illustrates one embodiment of the invention, the numeral 10 designates the front part and the numeral 11 designates the rear part of a two-part microphone housing having a substantially central parting plane. Parts 10 and 11 are preferably molded from plastic material to substantially cup-shaped form with their edges in engagement to define a chamber 12 therebetween. The margins of the housing parts are secured together in face engagement by screws 13, or the like. The part 10 has a plurality of openings 14 formed therein for passage of sound therethrough and into chamber 12. Part 11 has a central projection 15 accommodating the formation of a tapered recess or pocket therein communicating with said chamber.

Each of the housing parts has a ring 16 fitting therein, and the margin of the diaphragm 17 is positioned between said rings in the parting plane of the housing. As here shown the diaphragm has a radial tongue-like projection 18 which may extend between the parting faces of the housing parts and is bent to extend through the wall of one of the housing parts and project therefrom to form one terminal 19 of the microphone. As

2

illustrated tongue 18 may be imbedded in part 11 during the molding of said part to provide a pre-assembled diaphragm and housing unit. Diaphragm 17 has a frusto-conical off-set portion 20 formed centrally therein. The pocket formed in projection 15 of housing part 11 mounts a cup-shaped frusto-conical metal lining plate or button 21 with which electrical connection is made by a conductor 22 projecting through the housing wall to provide a second microphone terminal 23. The central diaphragm portion 20 preferably projects into and is arranged coaxially with button 21, and said parts are so shaped and related that the spacing therebetween is substantially uniform at all points. Carbon granules 24, or granules of other suitable conductive material, fill the space between said diaphragm and button, and are confined therein by a suitable retainer ring 25 spanning the space between the diaphragm and the housing wall and positioned concentrically relative to diaphragm projection 20. Retainer ring 25 may be made of any suitable material having requisite properties of compressibility and resilience to permit vibration of the diaphragm responsive to sounds impinging thereagainst. Ring 25 is of a size to provide a substantial free space between the same and ring 16.

A thin sheet 26 of rubber or flexible plastic material is preferably positioned against the inner face of the apertured wall of front housing part 10 and is secured thereto at its margin, as by clamping thereof between said wall and the adjacent diaphragm seating ring 16 or by adhesive means. A ring 27, preferably of the same radial dimensions as ring 25, is positioned in coaxial relation to ring 25 and diaphragm projection 20 to span the space between the diaphragm and the sheet 26. Ring 27 is made of suitable yieldable resilient material, and preferably has substantially the same properties as ring 25. Thus a closed chamber is defined by sheet 26, ring 27 and the diaphragm, and any material 28 suitable to balance the pressure and vibration-damping action applied at the opposite face of the diaphragm 45 is confined in said chamber. A large variety of materials will satisfy the requirements for a balanced diaphragm. I prefer to use a granular material, and find that carbon granules, sand, or granules of any other material which are of approximately the same size and specific gravity as carbon granules will serve the purpose. It will be understood, however, that such materials are mentioned as illustrative only, and I do not limit the acceptable materials thereto, since any material which will equalize the pressure and vibra-

tion-damping effects on the diaphragm may be employed.

The construction described above, by providing for application of equalized pressures and vibration-damping effects upon the diaphragm, permits high fidelity response of the diaphragm. Unequal pressure application or damping of vibrations at opposite diaphragm faces tends to introduce distortion in the microphone vibrations and the response thereof to sounds and noises. In other words, in considering the wave form of vibrations of sound of a given frequency, and the vibration of the diaphragm responsive thereto, it will be apparent that application of similar conditions of pressure and vibration damping at the opposite diaphragm faces will result in true uniformity of the wave forms of the diaphragm and the transmitted signal on each side of the median line represented by the normal non-vibrating position of the diaphragm. Hence distortion is avoided, and any damping action upon the diaphragm is equal and opposite in character and does not interfere with true fidelity response of the diaphragm to the sound or signal applied thereto. Damping action on the diaphragm, to avoid undesirable effects, should be localized and applied at one point or portion only. Therefore, a substantial area of the diaphragm should be free from contact with other microphone parts, as illustrated; and the pressure balancing feature should preferably be incorporated in single button microphone only.

I claim:

1. A microphone comprising a hollow housing having an opening in one wall thereof, a diaphragm spanning said housing and having a central cup-shaped projection, a cup-shaped button in said housing spaced from said diaphragm and adjacent said diaphragm projection, a retaining ring encircling said button and spanning the space between said diaphragm and one housing wall, carbon granules in the ring-enclosed space between and engaging said diaphragm projection and button, a second retainer ring aligned with said first ring and spanning the space between said diaphragm and the other housing wall, and granular material confined in said last named ring and engaging said diaphragm within the cup-shaped portion thereof to dampen said diaphragm against harmonic distortion.

2. A microphone comprising a hollow housing having an opening in one wall thereof, a diaphragm spanning said housing and having a central cup-shaped portion, a cup-shaped button in said housing spaced from said diaphragm and adjacent said diaphragm projection, a retaining ring encircling said button and spanning the space between said diaphragm and one housing wall, carbon granules in the ring-enclosed space between and engaging said diaphragm and button, a second retainer ring aligned with said first ring and spanning the space between said diaphragm and the other housing wall, and a thin sheet of flexible material spanning said opening, and granular material within said last named ring between said sheet and diaphragm and within said cup-shaped projection for preventing harmonic distortion of said diaphragm.

3. A microphone comprising a chambered housing, a diaphragm spanning said chamber and having a central off-set, a recessed metal plate mounted in said housing in spaced coaxial relation to said diaphragm, a pair of similar annular retainers arranged in coaxial relation to

each other and to said diaphragm and spanning the spaces between said diaphragm and the opposite walls of said housing, carbon granules confined by one ring and engaging said diaphragm 5 end plate, and granular material confined by the other ring and engaging said diaphragm to counterbalance the pressure of said carbon granules on said diaphragm.

4. A microphone comprising a hollow housing, 10 a diaphragm in said housing defining opposed chambers therein, said diaphragm having a central cup-shaped portion, a contact in one chamber in spaced coaxial relation to said diaphragm, a pair of similar retainer rings arranged in coaxial relation to said diaphragm and each spanning a chamber, carbon granules confined by one ring and engaging said diaphragm and plate, and pressure equalizing means in the opposite chamber bearing against the center of said diaphragm to prevent harmonic distortion of said diaphragm.

5. In a microphone of the single carbon button type, a housing having a central off-set portion, a diaphragm in said housing, a contact button in said housing, carbon granules between and engaging said button and a portion of one face of said diaphragm at said off-set, and means engaging a portion of the other face of said diaphragm at said off-set in pressure balancing relation to said granules.

6. In a microphone, a hollow housing, a diaphragm in said housing, said diaphragm having a central offset a single contact plate in said housing, and a quantity of granular material 35 bearing against limited opposed portions of each of the two faces of said diaphragm to balance said diaphragm, one quantity thereof engaging said plate and being electrically conductive.

7. In a microphone, a hollow housing, a diaphragm in said housing, said diaphragm having a central offset a single contact member in said housing spaced from said diaphragm, a quantity of conductive granular material between and engaging said contact member and a limited portion of one face of said diaphragm at said off-set, and means engaging a registering portion of the other face of said diaphragm and applying thereto a vibration reaction substantially equal to that applied by said granular material.

8. In a microphone of the single button type, a chambered housing having a recess, a contact in said recess, a diaphragm spanning said chamber and having a central off-set projecting toward said recess, conductive granules bearing 55 against said contact and a limited portion of one face of said diaphragm, and means bearing against a limited registering portion of the other face of said diaphragm, said granules and means applying substantially equal pressures and vibration-damping factors to said diaphragm.
